UNITED STATES PATENT OFFICE

ARTHUR C. STOCKER, OF AUDUBON, NEW JERSEY, ASSIGNOR TO GENERAL ELECTRIC COMPANY, A CORPORATION OF NEW YORK

SYNCHRONIZATION IN TELEVISION AND FACSIMILE TRANSMISSION SYSTEM

Application filed October 21, 1930. Serial No. 490,237.

My invention relates to television and facsimile transmission systems and particularly to the synchronization of the transmitting and receiving apparatus of such systems. In the past, synchronization commonly has been effected by producing an alternating voltage at the transmitting station synchronous with the transmitter, transmitting it by radio or wire line to the receiving station and using it to control the speed of the receiver. Since the instantaneous value of that voltage determined the instantaneous position of the scanning apparatus of the receiver, any transient phenomena such as static, switching surges, etc. may cause the receiver to swing or hunt and may even cause it to fall out of step.

It is the object of my invention to provide an improved method and apparatus applicable to such systems whereby the occurrence of such transient phenomena is less liable to produce an objectionable effect on the receiver.

In carrying out my invention in accordance with the form thereof which I have chosen to illustrate, I employ as before a synchronizing signal comprising regularly recurring impulses which is produced at the transmitter and transmitted to the receiver.

At the receiver I divide the signal into two parts. One part I delay one or more whole number of cycles according to convenience and then combine the two parts to make up the complete signal according to which the synchronization is effected. Thus, with a sinusoidal or other perfectly recurrent signal voltage transmitted, the voltage delivered to the synchronizer would remain apparently unchanged. Any transient phenomena picked up in the transmission, being of a non-recurrent character, would be delivered to the synchronizer as two such phenomena, each of half value, and separated by a time equal to the time lag of the delaying apparatus. Synchronization is thus made steadier and less liable to failure due to the occurrence of transients. The possibility of two similar transients occurring at a time interval equal to the time lag

of the delay apparatus is so remote that such an occurrence may be neglected.

My invention will be better understood from the following description taken in connection with the accompanying drawings, 55 and its scope will be pointed out in the appended claims.

Referring to the drawings, Fig. 1 is a block diagram of a system involving my invention and Fig. 2 is a detail thereof. 60

In Fig. 1, I have represented at 1 the transmitter of the system; 2 represents the transmission system which may be radio, wire line or any other transmitting means; 3 represents the signal divider forming a 65 part of the receiver. By means of the signal divider the receiver signal is divided in the present case into two parts, one of these parts is subjected to the effect of the delay apparatus 4 which, as has already been 70 pointed out, causes a delay in the signal of one or more whole number of cycles. The two parts of the divided signal thereafter are united by the signal uniter 5 and the complete signal is then employed in the synchronizing apparatus 6 to control the speed 75 of the receiver.

The time delay apparatus 4 may comprise any well known form of apparatus suitable for this purpose. In Fig. 2, I have illustrated one form of apparatus that may be employed. In accordance with this figure, the signal divider comprises the transformer 8 having the two secondary windings 9 and 10 and the signal uniter comprises a similar 85 transformer 11 having the two primary windings 12 and 13. Connecting the windings 9 and 12, I have shown the generalized circuit diagram of an artificial transmission line which preferably is constructed to have 90 low attenuation and high phase rotation at the frequency which is used for synchronization. This circuit is of well known form and as shown includes the series inductances 15 and the cross-connected capacitances 16. 95 Connecting the windings 10 and 13 I have shown a well known form of attenuator which is represented as comprising the series non-inductive resistances 17 and the parallel resistance 18. It will be understood 100

that the purpose of the attenuator just described is only to effect the same attenuation in both parts of the signal.

While I have chosen to illustrate and describe my invention in its simplest form, namely, that in which the signal is divided into two parts one of which is delayed, it is not limited to such form inasmuch as the signal may, if desired, be divided into a greater number of parts of which a plurality of parts are caused to be delayed each a different number of whole number of cycles. Moreover if desired both or all of the parts may be delayed different whole numbers of cycles.

Various modifications may therefore be made without departure from the spirit and scope of my invention which modifications I aim to cover by the appended claims.

What I claim as new and desire to secure by Letters Patent of the United States, is:—

1. In a television or facsimile transmission system employing a synchronizing signal comprising regularly recurring impulses, the method of reducing the effect of transient phenomena on the synchronization which comprises dividing the synchronizing signal at the receiving station into a plurality of parts, producing a phase displacement of one of said parts a whole number of cycles and recombining the parts to make up a complete signal by which the synchronization is effected.
2. In a television or facsimile transmission system employing a synchronizing signal comprising regularly recurring impulses, the method of reducing the effect of transient phenomena on the synchronization which comprises dividing the synchronizing signal at the receiving station into a plurality of parts, delaying one part a whole number of cycles and recombining the parts to make up the complete signal by which the synchronization is effected.
3. In a television or facsimile transmission system employing an alternating current synchronizing signal, the method of reducing the effect of transient phenomena on the synchronization which comprises dividing the signal at the receiving station into two parts, delaying one part a whole number of cycles, and recombining the parts to make up the complete signal by which the synchronization is effected.
4. In a television or facsimile transmission system employing a synchronizing signal comprising regularly recurring impulses, means at the receiving station of said system for dividing the synchronizing signal into a plurality of parts, means producing a phase displacement of one of said parts a whole number of impulse cycles and means for recombining said parts to form a complete synchronizing signal.

5. In a television or facsimile transmission system employing a synchronizing signal comprising an alternating voltage, means at the receiving station of said system providing a divided path for the synchronizing signal, means arranged in one branch of said path for causing a delay in the signal therein of whole number of cycles, and means uniting said paths into a single path.

6. In a television or facsimile transmission system employing a synchronizing signal comprising an alternating voltage, means at the receiving station of said system forming a divided path having two branches, means in one branch for producing a time delay of a whole number of cycles of said voltage, means in the other branch for producing an attenuation substantially equal to that in the one branch, and means for uniting the signals of said branches.

In witness whereof, I have hereunto set my hand this 16th day of October, 1930.

ARTHUR C. STOCKER.
